UNITED STATES PATENT OFFICE.

CHARLES R. FRYE, OF EAST ST. LOUIS, ILLINOIS.

DEVICE TO FASTEN GRAIN-DOORS IN FREIGHT-CARS.

972,688.

Specification of Letters Patent. Patented Oct. 11, 1910.

Application filed May 1, 1909. Serial No. 493,386.

To all whom it may concern:

Be it known that I, CHARLES R. FRYE, a citizen of the United States, residing at East St. Louis, in the county of St. Clair and 5 State of Illinois, have invented new and useful Improvements in Devices to Fasten Grain-Doors in Freight-Cars, of which the following is a specification.

This invention relates to devices for fastening grain doors, the object of the invention being to provide a simple and effective device for fastening in place the grain doors of freight cars, enabling the same to be repeatedly used without injury to the car.

With the above general object in view the invention consists in the novel construction, combination and arrangement of parts herein fully described, illustrated and claimed.

In the accompanying drawings:—Figure 1 is a side elevation of a portion of a car body, showing a grain door fitted to the door opening therein and held by the fastening devices of this invention. Fig. 2 is a vertical transverse section through the same. Fig. 3 is a detail vertical cross section on an enlarged scale taken in line with two of the fastening devices. Fig. 4 is a similar section showing another application of the fastening bolt or screw. Fig. 5 is a detail section showing the use of a lag screw in connection with the bushing and grain door.

Referring to Fig. 1 of the drawings 1 designates a freight car body provided with the usual doorway 2 defined at opposite sides by 35 the door posts 3, 4 designating a grain door positioned in and across the doorway.

In carrying out the present invention, I prefer to line the inner faces of the posts with metal facing plates 5 in order to prevent anyone from driving nails, screws or other fastening devices through the grain door into the door posts. At suitable points in each of the posts 3, I insert metal bushings 6 of the main body portion of each of 40 which is cylindrical, of uniform diameter and internally threaded at its inner end as shown at 7. The opposite end of the bush-

ing is enlarged as shown at 8 to form an enlarged recess 9 for the reception of the flush seating head 10 of a door fastening bolt 11 50 the length of which is sufficient to pass entirely through the bushing and the face plate 5 and also through the door 4 within which the bolt receives a fastening nut 11'. The inner wall of the recess 9 forms a shoulder 55 against which the head 10 of the bolt or screw bears. The head of the bolt or screw is thus seated flush within the plane of the side of the car so that it may be removed from the outside.

In lieu of inserting the bolt 11 through the bushing from the outside, as indicated in Fig. 3, a comparatively short bolt may be inserted through the door 4 and into the inner end of the bushing 6 as shown in Fig. 4 65 so that the threads of the bolt are in engagement with the threads 7 in the end of the bushing. This enables the grain door to be securely fastened to the door posts from the inside and will also be found an effective 70 fastening device for the purpose set forth. Lag screws 12 may also be used in place of the bolts 11 said lag screws being inserted through the bushings and screwed into the grain door.

I claim:—

In a grain door fastening device, a door post, a metal bushing extending through the post and provided at one end with a chambered enlargement which is seated in a correspondingly formed recess in the post and engaged therewith to limit the movement of the bushing in the insertion of the same in the post, and door fastening means operatively associated with the bushing and with 85 the door to hold the latter in its closed position.

In testimony whereof I affix my signature in presence of two witnesses.

CHARLES R. FRYE.
